UNITED STATES PATENT OFFICE.

ALBERT G. REDMOND, OF INDIANAPOLIS, INDIANA, ASSIGNOR TO MARVEL CARBURETER COMPANY, OF FLINT, MICHIGAN, A CORPORATION OF INDIANA.

CARBURETOR.

1,412,137.

Specification of Letters Patent. Patented Apr. 11, 1922.

Application filed March 6, 1917. Serial No. 152,706.

To all whom it may concern:

Be it known that I, ALBERT G. REDMOND, a citizen of the United States, residing at Indianapolis, in the county of Marion and

- 5 State of Indiana, have invented certain new and useful Improvements in Carburetors, of which the following is a specification, reference being had therein to the accompanying drawing.
- 10 This invention relates to certain new and useful improvements in carburetors especially adapted to be used in connection with any of the small type of cars, the object being to provide a carburetor which is ex-
- 15 ceedingly simple and cheap in construction having only one moving part which is in the form of an auxiliary suction-controlled air valve which constantly proportions the mixture to the motor according to the speed
- 20 thereof by allowing a high speed jet to be uncovered so as to add additional fuel as the speed of the motor increases.

Another object of my invention is to provide a carburetor with a low speed jet so 25 constructed and mounted that a uniform carburetor is provided at all speeds, the low speed jet allowing the motor to idle properly, the high speed jet only being set in operation by the increasing suction of the

30 motor, the same being cut off automatically in order to obtain a maximum economy of fuel.

Another and further object of the invention is to provide a carburetor in which the 35 body and float fuel chamber is formed integral and connected by the usual fuel passages with high and low speed nozzles so as to give a constant supply of fuel to the nozzles, the low speed nozzle being controlled

40 by a needle valve from the dash in order to adjust the supply of fuel in proportion to the work required of the engines.

Other and further objects and advantages of the invention will be hereinafter set forth

45 and the novel features thereof defined by the appended claims.

In the accompanying drawings,

Figure 1 is a perspective view of my improved construction of carburetor;

50 Figure 2 is a longitudinal vertical section through the same showing the parts in position when the engine is running at low speed;

55 Figure 3 is a similar view showing the suction-controlled valve raised in order to

provide an additional air and fuel supply on the increased speed of the motor; and

Figure 4 is a section through the float and fuel supply chamber.

Like numerals of reference refer to like 60 parts in the several figures of the drawing.

In carrying out my invention I employ a horizontally disposed tubular body member 1 which is provided at one end with a flange 2 to facilitate its connection with the inlet 65 manifold of a motor, and in use has its other end open for the admission of air.

Formed integral with the horizontally disposed tubular body member 1 is a laterally extending float and fuel chamber 3 which 70 communicates with a fuel passage 4 through the medium of a valve seat plug 5 controlled by a needle valve 6 carried by an arm 7 of a pivoted float 8 so as to maintain a constant level of fuel within the chamber 3 in the 75 usual manner. The fuel passage 4 is enlarged at its outer end having its wall internally threaded to receive the threaded end of a fuel pipe 9. The fuel chamber is closed by a removable cover 11 secured in position 80 by screws as clearly shown in order to provide means for inserting and removing the float and needle valve or for repairing the same.

The under side of the tubular body member 1 is enlarged to provide a passageway 10 opening into the tubular body member at one end at 11', and its opposite end at 12 forming a by-pass for incoming air as will be hereinafter fully described. The enlarged portion of the body member under the by-pass is provided with fuel wells 13 and 14 which communicate with the fuel chamber by fuel passages 15 and 16, said wells being closed by plugs 13' and 14'. 95

The upper end of the fuel well 14 is provided with a threaded opening communicating with the by-pass in which is secured the threaded lower end of a low speed nozzle 17 which extends upwardly through the opening 12 into the portion of the body member, that is generally known as the mixing chamber, and is provided with a valve seat 18 adapted to be engaged by a needle valve 19 having a threaded portion mounted within the threaded portion of a plug 20 secured in a threaded bore formed in the body member and has a head 21 at its upper end forming means for connecting the same to the dash-control operating means in order to allow 110

the flow of fuel through the low speed jet to be controlled from the dash. The diameter of the opening 12 is greater than the diameter of the fuel nozzle 17 in order to provide 5 an annular passage around the fuel nozzle to allow air to circulate around the jet from the by-pass.

The well 13 communicates with the by-pass through a threaded bore in which is 10 mounted the threaded portion of a high speed nozzle 21 which extends into the tubular body member through an opening 22 having a diameter slightly larger than the diameter of the nozzle in order to allow a 15 small portion of air to circulate around the same as will be hereinafter fully described.

Extending transversely through the tubular body member 1 is a shaft 23 on which is pivotally mounted a suction-controlled valve 24 having an embossed portion 25 arranged over the high speed nozzle 21, the upper face of the embossed portion being provided with a positioning pin 26 over which is arranged a coil spring 27 which extends up into a cap 28 which is provided with a threaded portion working in an internally threaded boss 29, said cap having a milled head 30 which is adapted to be engaged by a spring 31 for holding the cap in its adjusted position in 30 order to adjust the tension of the spring so as to allow the suction-controlled valve to open at a pre-determined suction of the motor.

The suction-controlled valve 24 normally 35 lies with its free edge in contact with the inner wall of the body member so as to practically close the passage of air over the high speed nozzle, the opposite end of the suction-controlled valve being held in close 40 proximity to a plug 32 carried by a screw 33 which also holds the spring 31 in position to engage the milled head 30 of the cap member 29, and as shown in Fig. 2 the passage of air through the carburetor is through 45 the by-pass around the low speed nozzle.

When the vacuum is increased within the carburetor by the increased speed of the motor the suction-controlled valve is raised into the position as shown in Fig. 3 so as 50 to uncover the high speed nozzle, and the air passing over both of the nozzles proportionately increases the supply of fuel to the engine as the motor speed increases and as the speed of the motor is reduced the 55 vacuum within the carburetor is reduced and the suction-controlled valve closes so as to cover the high speed nozzle. By having the spring which is employed for holding the suction-controlled valve in closed position 60 adjustable, the carburetor can be set so that the high speed nozzle will be brought into operation at any desired speed of the motor.

The inlet end of the tubular body is provided with what is known as a choker valve 65 34 carried by a valve stem 35 which is pro-

vided with an arm 36 having one end of a coil spring 37 connected thereto for normally holding the valve in open position, the movement of the valve into closed position being limited by a stop screw 38.

When it is desired to start the engine so as to provide a rich mixture, the choker valve is closed which increases the vacuum within the carburetor so as to draw the fuel out of the nozzle. The outlet end of the 75 tubular body is provided with a throttle valve 39 carried by a valve stem 40 which is provided with an arm 41 having a depending lug 42 which is adapted to engage an adjustable stop screw 43 which allows the 80 throttle to be set so that the same can only be partially closed or completely closed.

The fuel supply chamber or bowl is provided with a valve-controlled drain plug 44 in order to allow the liquid to be drained out 85 of the bowl when desired.

From the foregoing description it will be seen that I have provided a carburetor in which a substantially horizontally disposed straight tubular body is employed having 90 spaced fuel nozzles one of which is normally covered by a suction-controlled valve which is open by the suction of the engine as the speed increases so as to increase the richness of the mixture, and by this construction 95 a very economical carburetor is provided which constantly proportions the mixture of air and gas according to the motor demand, and it will be seen that when the engine is idling the fuel is taken from the low 100 speed nozzle and the air is by-passed around the high speed nozzle, and at high speed a straight passage of air is obtained over the high speed nozzle so as to increase the richness of the mixture.

I claim:

1. A carburetor, comprising a horizontally disposed tubular body having a straight air passage therefrom, a suction-controlled valve disposed within said body for closing the 110 air passage thereof, said body having a depending enlarged portion provided with a passageway forming a by-pass around said valve, a low speed nozzle arranged in the outlet of said by-pass, and a high speed 115 nozzle arranged in a plane above said low speed nozzle under said suction-controlled valve.

2. A carburetor, comprising a horizontally disposed tubular body having a laterally extending float and fuel chamber, said body member having a straight air passage therethrough, a suction-controlled valve pivotally mounted within said air passage for normally closing said passage, said body member having a depending enlargement provided with a passageway forming a by-pass around said valve, fuel wells formed in said enlargements under said by-pass, fuel passages extending from said wells to said fuel 125 130 135

chamber, and fuel nozzles extending from said wells into said air passage one of said fuel nozzles being arranged under said suction-controlled valve.

- 5 3. A carburetor comprising a horizontally disposed tubular body having a straight air passage therethrough provided with a by-pass for the passage of air, said by-pass communicating with said air passage at its
10 ends and center, a suction controlled valve for closing said straight air passage, a high speed nozzle disposed in said air passage

under said suction control valve, a low speed nozzle disposed in said by-pass, a dash controlled valve controlling the low speed 15 nozzle, and a spring for holding the suction controlled valve in closed position.

In testimony whereof I hereunto affix my signature in the presence of two witnesses.

ALBERT G. REDMOND.
